UNITED STATES PATENT OFFICE

BERNARR MACFADDEN, OF NEW YORK, N. Y.

AIRPLANE-STOPPING DEVICE

Application filed February 23, 1929. Serial No. 341,983.

This invention relates to flying machines and airplanes and to apparatus or devices for stopping them, and more particularly to means for stopping airplanes on the landing field.

One object of the invention is to provide an apparatus or device of this kind which will quickly bring the airplane to rest on the field after it has landed.

Another object of the invention is to provide an apparatus or device of this kind which is suitable for short fields and which will permit economy in the area of fields.

Another object of the invention is to provide an apparatus or device of this kind with safe operating means which will operate when desired but not operate by accident.

Other objects of the invention will appear as the description proceeds; and while herein details of the invention are described and claimed, these are shown merely as examples, and the invention is in no way limited to these, since an entirely different construction may be used, or many and various changes may be made without departing from the scope of the invention as claimed in the broader claims.

The inventive features for the accomplishment of these and other objects are shown herein in connection with an improved airplane stopping device applied to an airplane having its wings each provided with a downwardly opening longitudinal cavity. The stopping device includes rollers disposed axially in said cavities, each carrying a retarding curtain having a weighted free edge. Means are provided for rotating the rollers, and to cause the rollers to rotate together. A door for the lower part of each cavity is provided with means for operating the door, and means for locking the door closed.

As the machine lands, the doors are opened, permitting the curtain to unwind and engage the air, to resist further travel of the plane, thus to bring it quickly to rest after which the curtain may be rewound.

In the accompanying drawing, showing by way of example, one of many possible embodiments of the invention,

Fig. 1 is a plan showing an airplane with my device applied thereto;

Fig. 2 is a side elevation showing the curtain lowered to operative position;

Fig. 3 is a fragmental plane, on a larger scale, showing the operating mechanism for the curtain and doors;

Fig. 4 is a side elevation showing the door-operating means and associated parts;

Fig. 5 is a transverse vertical sectional view, on a larger scale, and partly in elevation showing the cavity in the wing for the curtain, the curtain and door being removed, the section being taken substantially on the line 5-5 of Fig. 1, looking in the direction of the arrow; and

Fig. 6 is a fragmental vertical sectional view, on a larger scale, and taken on the line 5-5 of Fig. 1, the curtain and door being in place.

My improved airplane stopping device is shown in connection with a monoplane airplane comprising a fuselage 10, having stud beams 11 and 12 extending thereacross to which are secured front and rear wing beams 13 and 14 on which the wings 15 are built; though it is noted that the invention is in no way limited to monoplanes or to this type of airplane, as it may be applied to any type whatever.

A false beam 18 (Fig. 5) in the wing to the rear of and spaced from the wing beam is connected thereto by vertical webs 19 and 20, intermediate webs 20 being strengthened by strips 21 and cut away to form large downwardly opening recesses 22 forming a downwardly opening cavity in the wing extending to near the ends of the wings. Obviously, however, any desired construction of wing may be used.

Shafts 24 and 25 forming curtain rollers 26 (Fig. 6) disposed axially of said cavities are journaled in webs 19 and 27 (Fig. 1) at the ends of the cavity. The shaft 24 (Fig. 3) is here shown shorter than the other and terminates at the wall of the cock pit 28. The other shaft 25 is the longer and extends across the cock pit and is connected to the short shaft by a gimbal joint 29 to cause them to rotate together. If the shafts are axially alined this joint is not necessary.

A retarding curtain 35 (Fig. 6) secured on

the roller 26 of each of said shafts carries an iron bar 36 or other heavy weight secured to the free edge of the curtain, whereby the curtain may be caused to unwind by the weight 5 of the bar.

A sprocket wheel 37 (Fig. 3) is mounted on the short shaft; and a crank shaft 38 mounted on the wall of the fuselage in the cock pit is provided with a sprocket 39 connected by a 10 chain 40 with said sprocket 37, whereby the rods may be rotated to wind up the curtain.

A ratchet collar 41 may be, if desired, provided on the larger shaft, at one side of the cock pit. This ratchet is engaged by a pawl 15 42 pivoted on a base plate 43 secured at one side of the cock pit, to prevent the curtain from unwinding.

To prevent accidental displacement of the pawl from the ratchet, I provide a plate member 44 mounted on the top plate. This member, as shown, may be either a flat spring or a pivoted latch. The spring will permit operation of the pawl while engaged by the plate member. If the plate member is un- 20 yielding it must be pivotally mounted on the base plate and swing out of the way when the pawl is operated or disengaged.

In order to raise the pawl from the ratchet against the operation of the spring, I provide 30 a pivoted cam 44¹ pivoted on the base plate 43 and provided with a handle 44¹.

A hinge rod 45 (Fig. 6) passing through bearing plates 46 on said webs 20 just forward of the lower part of said recesses 22 35 extends across the cock pit and carries strap hinges 47 secured fast thereto, to which hinges are secured to doors 48, one for each of said cavities, whereby when the rod is rotated rearwardly a quarter turn, the door will 40 open downward permitting the curtain to unwind, if the pawl has been released.

A door-operating lever 50 (Figs. 3 and 4) fast on said hinge rod and provided with a transverse intermediate bore carries a bolt 51 45 slidable in said bore, and when the lever is in closed-door position, said bolt engages in one of a series of holes 52 in the plate, to prevent accidental opening of the door. A bolt-lever 55 has its intermediate part pivoted on the side of the lever 50 and its inner end pivoted to the bolt 51. A spring 56 compressed between the outer ends of the levers 50 and 55 serves for yieldably holding the bolt in the hole, and permits the withdrawal of the 50 bolt to release the lever 50 to open the door.

Both the door and the pawl and the ratchet are not necessary, but may both be supplied as extra precaution against accidental unwinding.

The operation is simple and obvious from the foregoing, but may be briefly summarized as follows:—

The curtains are kept normally wound up 65 and stored in their cavities, the door being locked closed, or the pawl engaged with the

ratchet or both, depending upon which are provided.

As the airplane is about to land the pawl is removed from the ratchet, as explained above. Then as, or just after, or even just before, the plane lands, the bolt 51 is withdrawn by operation of the lever 55, and the lever 50 lowered, thus opening the doors 48; whereupon the curtains, influenced by the weights 36, unroll and tend to hang in positions approximately indicated by the dotted lines of Fig. 2.

In these positions, the curtains engage the air and offer such resistance that the airplane is quickly brought to rest in much less space than heretofore.

Before the next trip the curtain is rewound by means of the crank 38 and sprockets; the pawl and latch plate 44 are replaced (if used); then the door is closed, and the lever 50 locked in door-closing position by means of the bolt 51.

I claim as my invention:

1. In combination, an airplane having its wings each provided with a downwardly opening longitudinal cavity; rollers disposed axially in said cavities; a retarding curtain secured on each roller; means for rotating the rollers; a weight secured to the free edge of each curtain; a door for the lower part of each cavity; and means for locking the door closed.

2. In combination, an airplane having its wings each provided with a downwardly opening longitudinal cavity; rollers disposed axially in said cavities; a retarding curtain secured on each roller; a weight secured to the free edge of each curtain; means to cause the rollers to rotate together; means for rotating the rollers; a door for the lower part of each cavity; means for operating the door; and means for locking the door closed.

3. In combination, an airplane its wings having each a downwardly opening longitudinal cavity near the rear edge extending to near the ends of the wings; shafts forming rollers disposed axially in said cavities and journaled at the ends of the cavity and extending into the fuselage of the airplane; a retarding curtain secured on each roller; a weight secured to the free edge of the curtain; means connecting said shafts to cause them to rotate together; a hinge rod mounted forward of the lower part of said cavities; a door for each cavity secured fast on said rod; an operating lever fast on said rod in the fuselage; and means for locking the lever in position to hold the door closed.

4. In combination, an airplane its wings having each a downwardly opening longitudinal cavity near the edge extending to near the ends of the wings; shafts forming rollers disposed axially in said cavities and journaled at the ends of the cavity and extending into the fuselage of the airplane; a

- retarding curtain secured on each roller; a weight secured to the free edge of the curtain; means connecting said shafts to cause them to rotate together; means for rotating the rods; a ratchet fast on one shaft; a pawl 5 engaging said ratchet to hold the shaft against unwinding movement; and means for locking the pawl on the ratchet.
5. In combination, an airplane its wings having each a downwardly opening longitudinal cavity near the rear edge extending to near the ends of the wings; shafts forming rollers disposed axially in said cavities and journaled at the ends of the cavity and extending into the fuselage of the airplane; a 10 retarding curtain secured on each roller; a weight secured to the free edge of the curtain; means connecting said shafts to cause them to rotate together; means for rotating the rods; a ratchet fast on one shaft; a pawl 15 engaging said ratchet to hold the shaft against unwinding movement; a hinge rod mounted forward of the lower part of said cavities; a door for each cavity secured fast on said rod; an operating lever fast on said rod in the fuselage; and means for locking the lever in position to hold the door closed.
6. In combination, a flying machine; a roller transverse to the path of the machine; a curtain on said roller having on its free 20 edge a weight sufficiently heavy to cause the curtain to unwind; and releasable means to hold the curtain from unwinding.
7. In combination, a flying machine having a downwardly opening cavity; a roller in said cavity; a retarding curtain secured to said roller and having a weight attached to its free edge; said roller being freely rotatable in unwinding direction, the weight being sufficiently heavy to cause the curtain to unwind; and releasable means for holding the curtain from unwinding.
8. In combination, an airplane having downwardly opening cavities in its wings; rollers in said cavities; a retarding curtain secured on each roller; weights secured to the free edges of the curtains, the rollers being freely rotatable in curtain-unwinding direction, the weights being sufficiently heavy to cause the curtains to unwind; and a door for the lower part of the cavity.
9. In combination, a flying machine having an elongated downwardly opening cavity transverse to the path of the machine; a roller disposed longitudinally in the cavity; a curtain wound around said roller and having a free edge; means for unwinding the roller; a door for said cavity; and a weight on the free edge of the curtain and adapted to hold the curtain lower than said roller when the curtain is unfurled.
10. In combination, a flying machine; a roller transverse to the path of the machine; a curtain on said roller having a weight on its free edge; and releasable means to hold
- the curtain from unwinding; said weight being adapted to hold the curtain lower than the roller when the curtain is unwound.
11. An airplane having a downwardly opening cavity transverse to the path of the airplane; a roller in said cavity longitudinally thereof; a curtain around said roller having a weight on its free edge; and a door for the cavity forming, when closed, a continuation of the lower surface of the wing and a part of the lifting surface thereof.
12. In combination, an airplane wing having a downwardly opening cavity transverse to its path; a roller in said cavity; a retarding curtain secured to said roller; means engaging the free edge of the curtain for causing the curtain to unwind and descend; and a door for said cavity completely closing the cavity and forming a continuation of the lifting surface of the wing.
13. In combination, an airplane having downwardly opening cavities in its wings; a retarding curtain secured in each cavity; weights secured to the free edges of the curtains; the weights being sufficiently heavy to cause the curtains to unfurl and descend; and a door for the lower part of the cavity.
14. In combination, an airplane wing; a curtain having one free edge secured under the wing transverse to the path of the wing; means for furling the curtain; and a weight on the free edge of the curtain heavy enough to unfurl the curtain.
- Signed at New York city, in the county of New York and State of New York, this 20th day of February A. D. 1929.
